ABSTRACT OF THE DISCLOSURE

A water cooled sewage pump having a cooling chamber surrounding the pump motor which receives cooling water by forced circulation from the pumped sewage. The pump impeller is provided with vanes which draw water from the pumped sewage while separating the sludge therefrom and causes it to circulate through the cooling chamber.

The present invention relates to a pump for sewage, pulp or the like. The sewage from a large number of buildings is collected in sewage stations or catch basins. Their location may be such that the water cannot flow by gravity to the sewerage system, for instance when the central main of the building runs below the sewerage system level or when the sewage is to be carried through elevated ground sections. In such cases pumps are usually used, which are specially designed for conveying sewage. These pumps have, i.a. a large-size impeller channel area in order to allow free passage of the sizable material.

The composition of sewage can be very variable especially if an industrial plant is connected into the sewage collecting station. Very commonly encountered sizable materials in sewage are cotton waste, nylons, towels and the like. In unfavorable circumstances such materials may cause breakdowns due to the obstruction of narrow passages which may exist in the pumps.

The size of the pump assemblies is to be reduced if low-price and lightweight pumps are to be provided. Since the pump unit itself has to be spacious in order to reduce the chances of obstruction, it is necessary to reduce the size of the motor unit. In this type of pumps which are mostly set up in moist chambers or submersed in water, the motor is fully enclosed and receives no ventilation, and therefore the dissipated heat has to be transferred through the motor casing wall to the surrounding air or water.

In order to reduce the size of the cooling surfaces and, consequently, that of the motor, the motor casing can be cooled with water or in any other way. Such a cooling can be achieved by bringing water to flow along the motor casing by means of a jacket surrounding said casing or by submersing the pump in the water so that the motor casing is at least partly submersed in the water.

It is also possible to have the cooling water sprinkling over the motor casing.

When pumping sewage by means of pumps submersed in it, a fully satisfactory cooling can be attained if a level control is provided in the sewage pit and the pump stopping level is set at such a height that a part of the motor casing is still submersed when the pump is stopped. It is however not always possible to keep the water level at the height required for an efficient cooling of such submersed pumps. This is for instance the case in basins with very large surface. Nor is a sufficient cooling provided if the pump is set up dry in a separate chamber aside of the collecting pit.

The motor casing can be cooled by water sprinkling, provided a separate well or the like is available. According to actual regulations the motor casing cooling device

2

may not be connected to the water main unless special safety measures are taken which, however, do not guarantee a reliable cooling in case the water main is shut off or a separate cooling pump breaks down, for instance.

It is a purpose of the present invention to avoid the above drawbacks by using the pumped medium for cooling the motor, said medium being supplied to a separate cooling chamber. The present invention is essentially characterized in that a sealing slit for the filtration of the sewage water to be used for cooling is formed between the upper peripheral edge of the pump impeller and the adjacent pump casing part abreast of the pump impeller edge. Cooling water relieved of impurities is thus supplied to said cooling water chamber, in the following called end cooling chamber. When pumping sewage, narrow channels are very likely to get stuffed with mud or blocked up by solid matters. In the pump of the invention the water is however relieved from larger sizable material and can therefore circulate in the cooling chamber, which makes it possible to use sewage water for cooling purposes.

According to a further embodiment of the invention the rear side of the impeller is provided with auxiliary vanes in order to create a certain back-pressure in the cooling chamber when the pump is started up as well as for the cooling water circulation.

A further embodiment of the invention is characterized in that the pump motor casing is provided with a surrounding cooling jacket and that the jacket cooling water chamber thus formed between the motor casing and the cooling jacket is provided with a cooling water inlet connected to the end cooling chamber between the impeller and the pump cover near the pump impeller periphery and with a cooling water outlet near the pump impeller nave.

The invention will be described more in detail below reference being made to the attached drawing which shows an embodiment of the invention.

In the embodiment shown, the motor casing is mounted on the pump casing 5. The motor casing is surrounded by a cooling jacket 2 which, for instance, can be constituted by a separate member having for instance a slightly conical shape, said member being mounted outside the motor casing 1. Alternatively, the cooling jacket may be cast integrally with the motor casing.

The pump casing 5 is provided with a large size flow-through area. This also applies to the impeller 6 driven by a motor shaft 19. An end cooling chamber 17 is provided above the impeller 6 between said impeller and the motor end shield or pump casing cover 18, said end cooling chamber 17 being intended to cool the cover or the motor end shield 18 as well as the motor bearing adjacent the impeller.

The rear side of the impeller 6 is provided with vanes 8 in order to create a certain back-pressure in the end cooling chamber 17. It is thus prevented that sludge may penetrate through the sealing slit 12 formed between the upper edge of the impeller 6 and the adjacent edge flange 60 of the motor casing 5, or that sizable material or textiles may obstruct said slit or get twisted around the impeller.

Ducts 3 provided in the lower part of the motor casing 1 are connected to ducts 4 in the pump casing 5 in such a way that cooling water is circulated from the upper side of the impeller 6 through the cooling ducts 3 as well as the cooling ducts 7. Said circulation is produced by the vanes 8 provided on the rear side of the impeller 6. The cooling ducts 7 are connected in series and arranged so that the inlet to said ducts is located at the impeller periphery where a higher pressure prevails, while the outlet from said ducts is located near the im-

peller nave 9 where a lower pressure prevails. A number of partition walls 10 are provided inside the jacket chamber, which walls, as already mentioned, form ducts 7, running vertically in the embodiment shown, which ducts are communicating with adjacent ducts through ports 11.

As mentioned above, a sealing slit 12 is being provided between the impeller 6 and the pump casing 5 in order to prevent impurities from penetrating into the cooling chambers. Said slit is arranged in such a way that sides 13 of the impeller channel protrude beyond the inner wall 14 of the pump casing 5 in that a ring-shaped flange projects from said wall 14, the solid particles being flung past the slit opening to be carried out of the pump casing 5 by the water. The cooling jacket 2 is at its top and its bottom provided with threaded and plugged lugs (15, 16 respectively), which can be used for flushing the cooling system when overhauling the pump, for instance.

Owing to the division of the jacket cooling chamber in a number of cooling channels arranged along a meander-shaped path, water flows through said channels at a high velocity so that obstruction of the channels through mud deposits is avoided.

The flow velocity of the cooling water can be further increased by arranging the cooling water inlet in a direction corresponding to a helical line around the cooling jacket.

Eventually the impeller may also be provided with vanes between the underside of the impeller and the bottom of the pump casing, and communication ducts may be provided between the cooling water chamber thus formed and the inlet and outlet ducts of the jacket cooling chamber as indicated by dashed lines on the drawing.

The device of the invention operates as follows:

When the pump is started the water above the impeller 6 is imparted a rotating movement by vanes 8 on the impeller rear side and the water is pumped into the cooling ducts 4, 3 and 7, further through the ports 11 to the next cooling duct to be discharged through the outlet 17 near the impeller nave 9. The cooling water further flows past the cooled rear side of the impeller 6 and is again pumped into the cooling channels 4, 3 and 7. In addition, an exchange of cooling water occurs at the slit 12 which operates as a filter. As already mentioned, the provision of a number of ducts with a comparatively small area brings about a high water flow velocity preventing the small particles from settling in the channels and carrying away the air which initially is enclosed at the upper part of the cooling channels. Practical tests have shown that enclosed air, if any, is discharged from the pump casing through the slit 12 and that the whole cooling chamber gets rapidly filled with water.

If, when pumping pulp or the like, a sufficient separation of the particles cannot be attained, the jacket cooling chamber can instead be used for additional separate cooling, the cover 18 being replaced by a cover without duct openings or the cover being displaced so that the duct openings are obturated by an overlying or subjacent member, or the duct openings being obturated by means of plugs of a resilient material so that the additional separate cooling can be achieved by connecting pipes for a cooling medium to the lugs 15 and 16. This embodiment can also be used for pumping hot liquids.

The additional cooling can also be used if a dilution of the pumped medium is permissible, in which case the coolant is supplied through the lug 15 or 16, and flows through the slit sealing into the medium being pumped.

5 This embodiment is also suitable when it is desirable that the diluent be well mixed into the medium being pumped.

With the embodiment described above the pumping can be carried out continuously without overheating the motor, whether the pump is submersed in water or not.

Although the invention has been described in connection with an embodiment shown on the drawing, it is obvious that may alterations or modifications may be made within the scope of the appending claims.

What we claim is:

15 1. A sewage pump comprising an impeller, a motor driving said impeller, a pump housing surrounding said impeller, and a pump motor casing over said motor, said casing having a cover at one end thereof adjacent said pump housing defining an end cooling chamber, a cooling jacket surrounding said motor casing forming an annular cooling chamber therebetween, a sealing slit between the upper peripheral edge of said impeller and the adjacent pump housing portion abreast of said impeller periphery, and auxiliary vanes on the upper side of said impeller, 20 whereby said auxiliary vanes cause cooling water free of impurities to circulate through said sealing slit, said end cooler cooling chamber and said cooling jacket, said cooling water entering said cooling jacket through an inlet connected to the end cooling chamber between said impeller and said pump housing near said impeller periphery and said cooling jacket having a cooling water outlet near the nave of said impeller.

25 2. A sewage pump as in claim 1 wherein said pump is further provided with an additional sealing slit between the lower peripheral edge of said impeller and the adjacent pump housing portion abreast of said impeller periphery.

30 3. A sewage pump as in claim 1, wherein the end cooling chamber is divided by a wall essentially parallel to the casing cover and provided with a ring-shaped opening around the pump driving shaft whereby said cooling chamber is divided into a first end cooling chamber part adjacent to said impeller where a higher pressure prevails and a second end cooling chamber part adjacent to the casing cover where a lower pressure prevails.

35 4. A sewage pump as claimed in claim 3, wherein the water inlet to the jacket cooling chamber is connected to the first end cooling chamber part and said water outlet is connected to the second end cooling chamber part.

40 5. A sewage pump as in claim 3, wherein the outlet from the jacket cooling chamber is located at the second part of said jacket cooling chamber.
